UNITED STATES PATENT OFFICE.

MAX KLITZSCH AND FRANZISKA KLITZSCH, OF LEIPZIG, GERMANY.

REGISTERING-VALVE.

1,084,015.

Specification of Letters Patent.

Patented Jan. 13, 1914.

Application filed October 31, 1912. Serial No. 728,923.

To all whom it may concern:

Be it known that we, MAX KLITZSCH and FRANZISKA KLITZSCH, subjects of the German Emperor, residing at Leipzig, in Germany, have invented certain new and useful Improvements in Registering-Valves, of which the following is a specification.

This invention relates to valves provided with registering mechanism, and more particularly to faucets or cocks for delivering beer and other beverages, and consists in combining a valve with mechanism which is actuated, for opening the faucet, by applying the glass or other receptacle to be filled, and actuates a counting device whereby the number of glasses of liquid drawn off is indicated.

The invention is illustrated in the accompanying drawing, in which:—

Figure 1 is a front view of the device partly in section, Fig. 2 being a section on the line A—B of Fig. 1, Fig. 3 is a perspective view, Fig. 4 a detail view partly in section. Fig. 5 illustrates a modification of a part of the arrangement.

In the construction illustrated in Figs. 1 to 4 the faucet 3 is connected by a nut 9 to the spout of an ordinary faucet 1, which is provided in the usual manner with a handle 2. The spigot of the faucet 3 is provided with two curved depending arms 4, 5, the lower ends of which abut on tappets 6 projecting from vertically movable rods 7 and 8. The latter are guided in holes in a plate 30 secured inside a housing 13 surrounding the faucet 3, and the rods carry at their lower extremities small arched plates 16, located within channels 14, and 15, respectively, the walls of these channels being formed by the housing and by vertical plates 14¹, 15¹ secured to the plate 10. The upper ends of the rods 7, 8 have lateral extensions from which project pins 17 engaged with arms 11, 12 fixed to the actuating spindles of two counting devices or meters 20 and 21.

The latter may be provided with any desired number of numeral disks, five being shown in the example illustrated. The spigot of the faucet 3 is provided with an arm 22, to which is connected a spring 24 attached to the housing and tending to hold the spigot in its closed position.

The end of the spigot projecting out of the shell has a flat part 23, the face of which abuts, when the faucet is closed, against a short arm 25, projecting from the upper

end of a vertically movable rod 26; this arrangement forms a locking device whereby the spigot is prevented from being rotated into its open position. Said rod 26 projects through a hole in the plate 10 and terminates at its lower end in the channel 15^a, which is at the same distance from the spout of the faucet 3 as the channel 15. The rod 26 is also provided with a lateral depending arm 27 which is located in a channel 14^a, the latter being at the same distance from the spout as the channel 14. The lower extremities of the rods 26 and 27 are provided with curved plates 30.

The faucet 1 is normally open, and the faucet 3 normally closed. For drawing off a large glass of liquid, the glass is inserted into the housing 13, from below, and is raised so that its rim enters the channels 14 and 14^a abuts against the outer plates 16 and 30, and pushes up the rods 7 and 26. By this means the arm 25 is removed from the flat part 23 of the spigot, and the tap-pet 6 of the rod 7 is caused to raise the arm 4, rotate the spigot, and open the faucet. The end of the arm 25, which abuts against the flat part 23, is rounded off so as to allow the spigot to begin its rotation immediately the rod 7 is lifted, but the rotation allowed by this rounding off is not sufficient to allow the spigot to rotate into open position without the arm 25 being removed from the flat part 23. When the glass is full, it is lowered, and the faucet 3 is closed again by the spring 24, the rods 7 and 26 returning by gravity to their original positions. In order to prevent excessive frothing when filling the glass the conical casing 13 is provided with a lateral gap which enables the glass to be tilted, and the faucet 1 may also be temporarily closed to cut off the flow of liquid and allow the froth to settle.

During the lifting of the rods 7 and 26 as described, the arm 11 of the meter 20 is raised by the lower pin 17 on the rod 7 and the meter registers one unit.

For filling a small glass the same is pushed up into the channels 15 and 15^a, so that in this case the rod 8 is raised, together with the rod 26. The action is the same as that previously described, with the exception that in this case the spigot is opened by the rod 8 and arm 5, and the meter 21 is actuated.

The glasses fit into their respective channels 14, 14^a and 15, 15^a sufficiently closely to

prevent an instrument from being inserted between the glass and the channel walls for the purpose of keeping the rods raised independently of the glass. Tampering with the device for the purpose of drawing off liquid without registering the operation, is also largely prevented by the provision of two rods (7 and 26 or 8 and 26) which have to be raised simultaneously to open the 10 faucet.

In the modification shown in Fig. 5 the meters 20¹ and 21¹, equivalent to the meters 20 and 21, are arranged so that the numerals are exhibited at the side of the faucet and 15 can thus be inspected both by the person drawing off the liquid and by a person in front of the refreshment bar or the like at which the faucet is used.

The channels into which the glasses are inserted may be provided with continuations extending around the rear part of the housing. 20

What we claim as our invention and desire to secure by Letters Patent of the United 25 States is:—

1. The combination of a valve and means for separately counting glasses of different sizes, said means including a plurality of counting devices, a housing having channels severally enabling the rims of receptacles of different sizes to enter same, and actuating devices severally constructed for collectively opening said valve and operating one of said counting devices, said actuating devices being severally provided with means enabling same to be severally operatively engaged with the rims of receptacles inserted into said channels. 30

2. The combination of a valve, a counting 40 device, actuating mechanism for collectively opening said valve and operating said counting device, a device for locking said valve in its closed position, and a housing having channels enabling the rim of a re-

ceptacle to enter same, said actuating mechanism and said locking device being severally provided with means for operative engagement with a receptacle-rim inserted into said channels, whereby said locking device is disabled prior to the opening of the valve 50 and actuation of the counting device. 45

3. The combination of a valve having a rotatable spigot, means for rotating said spigot to its closed position, an arm fixed to said spigot, a counting device having a spindle, an arm fixed to said spindle, a housing surrounding said valve and said counting device and having a channel enabling the rim of a receptacle to enter same, and a movable rod operatively engaged with both said 60 arms and terminating at one end in said channel. 55

4. The combination of a valve having a shell and a rotatable spigot, means for rotating said spigot to its closed position, a projection fixed to said spigot and having a flat face outside the valve shell, an arm fixed to said spigot, a counting device having a spindle, an arm fixed to said spindle, a housing surrounding said valve and counting device and having an opening enabling the rim of a receptacle to be inserted into same, a rod engaged with both said arms and arranged to be operated by a receptacle rim inserted into said opening, and a movable 75 member normally abutting against said face, to prevent rotation of the spigot, said movable member having a part arranged in the path of a receptacle rim entering the said opening. 80

In witness whereof we have signed this specification in the presence of two witnesses.

MAX KLITZSCH.
FRANZISKA KLITZSCH.
